CLAIM

The ornamental design for a cash register as shown and described.

DESCRIPTION

1. Cash register

1.1: Front

1.2: Back

1.3: Left

1.4: Right

1.5: Top

1.6: Bottom

1.7: Perspective

The dot-dot-dash broken lines seen in Reproductions 1.3, 1.4, and 1.7 define the bounds of the claim, which extends to the boundary but does not include the boundary line. All other broken lines depict portions of the cash register that form no part of the claimed design.
